JOURNAL BOX GUARD

Carl Vincent, Chicago, Ill., assignor of one-fourth
to Philip Pinsof, Chicago, Ill.

Application March 1, 1948, Serial No. 12,271

1 Claim. (Cl. 286—6)

1

This invention relates to improvements in dust guards for use in journal boxes of railway vehicles.

One of the objects of this invention is to provide a dust guard that will effectively keep dirt, dust and cinders out of the journal box and at the same time minimize the loss of oil from the journal box.

Another object of this invention is to provide a dust guard that is constructed in such a manner that it will effectively keep dirt out and keep oil in the journal box for a much longer time than other dust guards now used on railroad cars do, and without replacing or renewing any parts of the guard.

A feature of this invention is the fact that the elements which seal the journal box do not, like most dust guards, encircle the axle or shouldered portion of the axle and still allow the axle to rotate frictionally within the dust guard, but certain sealing elements rotate with the axle while other sealing elements remain stationary.

The guard of this invention is composed of a sleeve that is secured to the axle or journal collar, a ring that encircles the sleeve and is adjustably fastened to it, which ring has an outwardly extending rim around the center of its outer circumference, a frame to fit the slot provided in the journal box housing, which frame has a central opening so as to encircle the axle, sleeve and ring and which frame has a recessed groove extending all around the central opening and, when the device of this invention is assembled in the journal box and around the axle, said outwardly extending rim is slidably rotatable in said recessed groove.

A preferred and practical embodiment of the invention is illustrated in the accompanying drawing, in which

Fig. 1 is a face view of the dust guard for the journal bearing.

Fig. 2 is an enlarged sectional view along line 2—2 of Fig. 1 of the dust guard mounted on the axle.

Fig. 3 is a detailed sectional view of the dust guard assembled on the car axle and in position in the housing of the journal box shown in partial outline.

Fig. 4 is a view of the drive keys as seen when looking down at it along line 4—4 of Fig. 2.

Fig. 5 is a detailed sectional view of the drive key along line 5—5 of Fig. 2.

In the several figures of the drawing similar reference characters designate corresponding parts of the device of the invention.

2

A face view of the dust guard of this invention is shown in Fig. 1 in which 1 is a cross sectional view of the axle, 2 is the detachable face plate of the guard fastened in place by a series of 5 set screws represented by 3. A ring 4 is slidably fastened to sleeve 5 which is fastened securely to axle 1 by set screws represented by 6.

Fig. 2 is an enlarged sectional view of the dust guard along line 2—2 which shows some of the 10 details of construction of the device of this invention. The axle 1 is shown in broken section and the top portion shows the sleeve 5 which is wider than the ring 4 held in place around the axle by set screw 6. A cross section of ring 4 15 shows a central peripheral flange or rim 7 which extends radially outwardly as shown around the outside circumference of ring 4. The rim 7 extends into a groove formed by the retaining frame 8 of the guard, which was not visible in 20 Fig. 1, and the face plate 2.

The bottom portion of Figure 2 shows another cross section of sleeve 5 at a point where there is a slot 9 through the sleeve 5 to accommodate a 25 drive key 10 of push-button type of construction, which push-button drive key is assembled in a metal capsule 11 and inserted in an opening drilled in ring 4.

Fig. 3 illustrates the dust guard in the recess provided for it in the housing of the journal box shown in outline as 12, which recess is necessarily slightly wider than ring 4 but much narrower than sleeve 5. It is a sectional view also along line 2—2 of Fig. 1 with the axle removed to show detail of the inside face of sleeve 5 but with the 30 position of the axle shown in outline at 13 and the shoulder of the axle in outline at 14. The portion of the inside face of sleeve 5 that is visible shows slot 9 and hole for set screw 6 although the set screw is not shown in this sectional view.

In Fig. 4 there is illustrated one of the features 40 of the invention. It illustrates the head of the plunger proper 10 of a self-contained spring-pressed plunger assembly 11 disposed in slot 9 of sleeve 5, showing the flattened sides of the head 45 of the plunger 10 for meeting the straight sides of the slot in such a manner that the rotary motion of axle 1 and sleeve 5 is translated by the plunger meeting the side wall of slot 9 in the sleeve 5 to the ring 4. As shown in the lower 50 portion of Fig. 2 the profile view of the plunger assembly is circular so that ring 4 can be slidably attached to or removed from sleeve 4. The slot 9 permits movement of the axle and sleeve back and forth within the limits of the slot when for 55 example the car wheel is passing along a curved

rail. A side thrust beyond the limits of the slot would, because of the circular contour of the spring-pressed plunger 10 in the direction parallel to the axle, cause the ring 4 to become dis- attached from sleeve 5. However, the ring is slid- ably adjustable on the sleeve so that it could be easily reassembled as part of the rotating unit comprising the car axle, the sleeve and the ring.

Fig. 5 shows another detailed sectional view of the spring-pressed plunger assembly 11, particularly the details of the plunger and spring mechanism which is fitted into ring 4. The several figures of the drawing show three assemblies 11 located at 120° from each other in ring 4. Likewise the several figures of the drawing show three set screws represented as 6 for securing sleeve 5 to axle 1. It is not an object of this invention to restrict the construction of the de- vice of this invention by limiting the disclosure or invention to any specific number of assemblies 11 to slidably attach ring 4 to sleeve 5, or to any specific number of set screws to securely fasten sleeve 5 to axle 1. However, a sufficient number of both the plunger assemblies and set screws must be employed so as to effectively accomplish their purposes and for reasons of strength, design and effectiveness they should be arranged at equal intervals from their respective counter- parts.

A special feature of the invention is the construction of the elements which keep the oil in the journal box and keep cinders and dirt out of the journal box, namely ring 4 which slidably rotates in frame 8. When face plate 2 is fastened in place by set screws 3 to the frame 8 there is formed a circular groove in which the central rim 7, which extends outwardly around the circumference of ring 4, frictionally rotates. It is also within the scope of this invention to have the rim extend inwardly from the frame of the dust guard and to have the groove formed as a recess in the rotating ring, so that in such construction the ring which rotates with the axle would be riding the rim of the frame like a double flanged wheel runs on a rail.

Dust guards on the market now are made from many different kinds of materials, such as non-ferrous metals, wood, leather, plastic materials, plywood, Bakelite, fibrous compositions and others. All of these materials have some value but none of them have proven completely satis- satisfactory for use in journal box dust guards, either because of cost, wearing value, replacement, breakage or simplicity of construction. The dust guard of the invention could probably be made to work effectively if made properly out of any of the aforesaid materials. However, in a preferred con- struction the device of this invention would be most practical if made of hard and long-wearing metal, like steel, with friction bearing metals for those parts which are in contact when elements of the device are slidably moving or rotating.

In order to obtain long life at minimum cost it is within the scope of this invention to use alloys and mixtures of metals. For those surfaces which move in contact with each other it is within the scope of this invention to use bronze, brass, or other compositions of friction bearing metals with

a view to obtain a maximum wearing quality at a low or reasonable cost of production. Of course the design of the device of this invention is pur- posely such that the entire dust guard may be re- moved and replaced by another in the journal box, and any of the worn, broken or failing parts may be replaced in the removed guard and it may be restored to use in the same or another journal box.

In the drawing and the description of this in- vention reference has been made to the applica- tion of the sleeve to the axle and the ring to the sleeve. It is also within the scope of this invention to attach the ring to the axle without using a sleeve by cutting slots in the axle for the drive keys. Likewise the application of either or both the sleeve and ring can be made to a journal collar or shoulder of the axle instead of the axle as is shown in the drawing.

What I claim is:

A dust guard for a journal box having an axle extending therethrough and provided with an in- ternal annular recess for accommodation of the guard, said dust guard comprising a cylindrical sleeve of a width substantially greater than said annular recess, means fixedly securing said sleeve on said axle in a position of approximate radial alignment with said recess, a ring member sur- rounding said sleeve and axially slidable thereon and fitted closely therearound in substantial seal- ing relationship with respect thereto, there being a plurality of axially extending straight-sided slots formed in said sleeve member at circumferentially spaced points therearound, there being a plural- ity of circumferentially spaced radially extending bores formed in said ring member in register with said slots, a self-contained plunger assembly dis- posed in each bore and including a spring-pressed plunger proper having an end projecting into one of said slots, said end of the plunger being formed with straight sides bearing against the sides of said slot for preventing circumferential turning move- ment of the ring member with respect to the sleeve and presenting rounded ends permitting forced re- moval of the ring member axially from the sleeve, an outwardly extending annular, radially disposed peripheral flange formed on said ring member centrally thereof, a two-piece separable retain- ing frame of ring-like configuration disposed 30 within the recess of said journal box and includ- ing a body portion and a face plate, and means 35 removably securing said face plate to said body portion, said face plate and said body portion forming therebetween an internal annular recess 40 into which said radially extending flange extends and in which it is rotatably confined.

CARL VINCENT.
